UNITED STATES PATENT OFFICE

2,605,906

Joseph F. Pontius, Alhambra, Calif.

Application January 4, 1949, Serial No. 69,174

1 Claim. (Cl. 211—106)

to a novel bumper for shaped m

This invention relates to a novel hanger for clothing and the like articles, the primary object of which is to permit occupants of an automobile to readily and easily suspend clothing on the retractable windows thereof.

A further important object of this invention is to provide a hanger constructed of a single piece of wire bent to form a plurality of vertically spaced laterally extending hooks.

A still further object of this invention is to provide a device of the character described including anti-friction means in the form of rollers carried by the bent wire for grippingly and yieldingly engaging both the sides and the free edge of the window.

A further object of this invention is to provide a device of the character described which can be readily and easily slipped on and off the window.

And yet another object of this invention is to provide a hanger for windows, constructed of a single piece of wire comprising a substantially U-shaped member having a first and second leg, vertically spaced hook members extending laterally from said first leg, and anti-friction means carried by the bight portion of said U-shaped member for grippingly engaging an edge of the window.

These, together with various ancillary objects and features of the invention which will later become apparent as the following description proceeds, are attained by the device, a preferred embodiment of which has been illustrated by way of example only in the accompanying drawings, wherein:

Figure 1 is a perspective view of one modification of the device shown attached to a window;

Figure 2 is a perspective view of another modification of the device shown attached to a window; and

Figure 3 is a sectional view taken substantially on a plane of section line 3—3 of Figure 1.

Specific reference is now made to the drawings. In the several views in the accompanying drawings and in the following specification similar reference characters indicate corresponding elements throughout.

Indicated generally at 10 is a window pane having a top edge 12 and sides 14 and 15. It is to be understood that while this glass pane may be any type of support, it is particularly contemplated that it refer to retractable windows in automotive vehicles. The device indicated generally at 16, and shown clearly in the drawings, is made of a single piece of wire bent to form a U-

shaped member having one leg 18 and another leg 20 joined by a bight portion 22.

5 The leg 18 is bent and configurated as shown in the drawings to provide vertically spaced, laterally extending clothes retaining hook members 24 and 26. It will be noted that each of the hook members 24 and 26 consists essentially of adjacent extensions 28 and 30 which are portions originally of the leg member 18. The extensions 10 28 and 30 are secured together by means of an appropriate fastening band or wire 32. The bottommost extension 30 is further bent to produce a laterally extending bottom hook member 34.

15 It will readily be seen that the hanger can be easily slipped on and off the window 10 and to support the hanger on the top edge 12 of the window an anti-friction roller 36 in the form preferably of a hard rubber roller is journaled on the bight portion 22. A means is provided for 20 yieldingly and grippingly engaging the sides 14 and 15 of the window which consists of the following elements. An open loop 38 is carried at the bottom end of the leg 20 and journals an anti-friction roller 40, also preferably of hard 25 rubber, which roller engages the side 15 of the window 10. The bight portions 42 and 44 of the leg 18 between the hook members 24 and 26, and the hook members 26 and 34 are also provided with anti-friction rollers 46, also preferably of hard rubber, for grippingly engaging 30 the side 14 of the window 10.

35 In the modification shown in Figure 2, virtually the same construction as that shown in Figure 1 is provided with the exception that one of the hook members, either 24 or 26 is excluded therefrom. As shown, therefore, the hanger in Figure 2 includes a U-shaped member having a leg 48 joined by a bight portion 50 to a leg portion 52 which carries an open loop 54 at the bottom end thereof. The leg 48 is bent to form a laterally extending hook member 56 having adjoining portions 58 and 60 attached to each other by means of a wire 62. The adjoining portion 60 is further bent to form a bight portion 62 and the laterally extending hook 64 at the end thereof. 40 45 As in the modification shown in Figure 1, the bight portion 50 journals an anti-friction roller 66 for suspending the hanger upon the top edge 12 of the window, while the open loop 54 and the bight portion 62 each journal an anti-friction roller 68 for grippingly and yieldingly engaging the sides 14 and 15 of the window. 50

In view of the foregoing description taken in conjunction with the accompanying drawings 55 it is believed that a clear understanding of the

device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A hanger for windows constructed of a single piece of wire comprising a substantially U-shaped member having a first and second leg connected by way of a bight portion, said second leg terminating in an open loop, an anti-friction roller carried by said loop for yieldingly and grippingly engaging one side of the window, an anti-friction roller carried by the bight portion of said U-shaped member for engaging the edge of the window, the free end of said first leg being upturned to form a hook, a pair of vertically spaced hook members formed from said first leg and located between said upturned hook and said bight portion and extending laterally from said

first leg, said hook and hook members progressively increasing in lengths from the free end of the first leg to said bight portion, each hook member embodying side-by-side extensions having wire wrappings thereon, and anti-friction rollers on the first leg between the hook members and between the upturned hook and the adjacent hook member for grippingly engaging the other side of the window.
